US0D1039525S

(12) **United States Design Patent** (10) Patent No.: **US D1,039,525 S**
(45) Date of Patent: ** Aug. 20, 2024

(54) **SMARTWATCH**

(71) Applicant: **SHENZHEN DO INTELLIGENT TECHNOLOGY CO., LTD.**, Shenzhen (CN)

(72) Inventors: **Yanxiong Zhu**, Guangdong (CN); **Peng Li**, Guangdong (CN)

(73) Assignee: **SHENZHEN DO INTELLIGENT TECHNOLOGY CO., LTD.**, Shenzhen (CN)

(**) Term: **15 Years**

(21) Appl. No.: **35/516,462**

(22) Filed: **Jan. 18, 2023**

(80) **Hague Agreement Data**

Int. Filing Date: **Jan. 18, 2023**

Int. Reg. No.: **DM/226940**

Int. Reg. Date: **Jan. 18, 2023**

Int. Reg. Pub. Date: **Mar. 3, 2023**

(30) **Foreign Application Priority Data**

Nov. 18, 2022 (CN) 202230772788.3

(51) **LOC (14) Cl.** **14-02**

(52) **U.S. Cl.**

USPC **D14/344**; D10/32
